UNITED STATES PATENT OFFICE

WILLIAM ERASTUS WILLIAMS, OF WILMETTE, ILLINOIS.

REINFORCED DISK WHEEL.

Application filed April 1, 1922. Serial No. 548,619.

To all whom it may concern:

Be it known that I, WILLIAM ERASTUS WILLIAMS, a citizen of the United States, a resident of Wilmette, in the county of Cook and State of Illinois, have invented the new and useful Improvement in Reinforced Disk Wheels, of which the following is a specification.

The object of my invention is to provide 10 a strong disk wheel and one that may be cheaply made and be sufficiently light and yet stiff around the hub zone without the necessity of employing what is known as a tapered disk for the web of the wheel and 15 in place of using a tapered disk I reinforce the disk by a secondary disk around the hub zone.

The invention is set forth in the claims. Reference will be had to the accompanying drawings in which Figure 1 is a front elevation of a wheel.

Figure 2 is a sectional elevation.

Figure 3 is an enlarged detail showing an alternative construction.

25 In the drawings 1 indicates the hub of an automobile wheel herein shown as being a rear wheel of a peculiar type. 2 indicates the brake drum and 3 indicates the rim, here shown as the type, known as quick detachable, used with a straight side tire and provided with the detachable side ring 4. The web of my wheel I prefer to make of a disk of metal of uniform thickness, forming what may be termed the front or outside 35 face of the wheel and this disk is of relatively light material and is shaped with an annular seat 5 on the hub barrel, which seat forms a part of a flange or margin of a straight faced portion of the disk 6, through 40 which there passes a series of stud bolts 7 securely fastened into a flange 8 of the hub and provided with nuts 9 adapted to screw on to the studs 7 and thereby fasten the disk to the hub in a fashion. Lock washers 10 45 prevent the nuts from accidentally becoming loose. The annular zone 6 of the front disk is bent inwardly to form an inclined zone 11 which terminates in a concave convolution 12 merged into an annular convex sur- 50 face 13 and this in turn merging into a con- 55 face 14 which extends up to and joins the rim at the seat 15 underneath the portion of the rim wherein the projection 16 of the side ring 4 is seated.

55 This seat 15 of the disk on the rim is made secure against side skin shocks by means of

the little swell 17 on the inside and the little flange 18 on the outside, which holds the disk into the rim by the shoulders thus formed. The shoulders are formed by dies 60 or rollers and one at least is formed after the rim and disk are placed in proper relative positions; and as a further security, the rim and disk are united by spot welds 19.

To assist the main or front disk in sustaining strains near the hub I provide a secondary or reinforcing disk on the inside of the main disk, which reinforcing disk terminates in a region not quite midway between the hub fastening and the rim, as indicated by 20. This secondary disk fits the convolutions of the front or main disk in the same manner as though it were a unitary part thereof, and an inclined portion of this secondary disk, indicated by 21 is seated at 7e. 22 on an inclined flange 23 of the hub 1.

The peculiar shape of the main and secondary disks where they join each other, is such that the carrying loads that come upon the main disk are shared by the closely fitting offsets of the disks and hub. Thus the outer margin 20 of the secondary disk and the inclined surface 21 thereof, in connection also with the inclined surface 24, takes vertical loads direct from the main disk to the secondary disk. In addition to the feature of reinforcing the main disk by the arrangement of the shapes as described, I also connect the two disks by other suitable means, e. g., a series of spaced spot welds in the inner and outer zones, 6, 25, of the reinforcing disk.

This also is assisted by the fastening nuts 9 which clamp the two parts together in this region. The spot welds in this zone 6 are 95 indicated by 26 and may be placed at other sections of the contacts between the two disks, as may be desired.

Thus by means of making the reinforcing disk fit the main disk in the shapes as shown, 100 I am able to make a very cheap wheel and at the same time a light one, making unnecessary the prepared tapered disk which is an expensive item to make compared with the flat sheets which compose my two disks. 105

The fastening which I have provided at the rim is a very cheap and secure one and gives a pleasing and easily cleaned front wheel-face.

To allow inflating and testing tire pressure while operating from the outer side of the wheel, the main disk is perforated at 110

27 so that the common straight valve stem may project to the front side of the disk.

In place of securing the disk to the rim as shown in Figure 2 and described I may, 5 if I choose turn the outer edge of the main disk inwardly in the form of a flange 28 and secure it to the rim by the rivets 29 as shown in Figure 3.

What I claim is:—

10 1. In a device of the class described, a relatively thin disk forming the front face of a wheel and of uniform thickness and provided with a series of inclined faces around the hub zone; in combination with 15 a reinforcing disk on the inside of the wheel and fitting the convolutions of the main disk.

2. In a device of the class described, a disk forming the web of the wheel and being relatively thin and of uniform section; in combination with a reinforcing disk for a distance around the hub zone and the two disks united together and having convolutions forming shoulders adapted to aid the 25 main disk in transmitting its load to the reinforcing disk.

3. In a device of the class described, the combination with a main disk of uniform thickness having a central marginally 30 flanged hub receiving opening surrounded by a normally vertical plane zone, of a series of fastening screws passing through this zone, which merges peripherally into an inwardly inclined zone continuous peripherally with successive concave and convex annular zones and with a wider concave zone extending to the rim, and a central reinforcing disk fitting throughout its 35 extent the various main disk zones which it overlaps.

4. In a wheel of the class described, a disk of uniform thickness making the main portion of the disk and provided with a centering seat on the hub and an inclined 45 bearing on a flange of the hub, and reinforced with the disk extending from the hub outward for a distance approximating one half of the radius of the wheel.

5. In a wheel of the class described, a 50 disk of uniform thickness forming the web of the wheel and having a convex convolution around the hub, with a concave main

body portion for the outside of the wheel; in combination with a reinforcing disk around the hub zone covering the convex 55 portions of the main disk.

6. In a wheel of the class described, a disk of uniform thickness forming the main web of the wheel and having a series of annular ribs or corrugations around the hub zone; 60 in combination with a reinforcing disk united to the main disk, and covering a region around the hub zone only.

7. In a wheel of the class described, a disk forming the web of the wheel composed 65 of a uniform section of metal and having convolutions around the hub zone whereat the disk is fastened to the hub; in combination with a reinforcing disk dished outward from the hub and fitting closely the convolutions 70 of the main disk and united to the main disk at different points.

8. In a wheel of the class described, a main disk forming the main web of the wheel, concave as relates to the region approaching the rim and convex as to the region around the hub zone and reenforced with a secondary disk fitting on the inside of the main disk and fastening thereto.

9. In a wheel of the class described, a 80 disk forming the main web of the wheel of relatively thin metal, a rim having an inward projecting portion and the said disk secured to the rim on this inward projecting portion by means of having the margin of the disk curved to form a shoulder on each side of the inward projecting portion of the rim.

10. In a wheel of the class described, a concave disk forming the major portion of 90 the web of the wheel and joined to the rim by having the margin of the disk formed into ribs adapted to embrace both sides of a narrow portion of the rim; in combination with a rim having a narrow inwardly 95 extended portion to which the disk is secured.

Signed at Chicago, in the county of Cook and State of Illinois, this 28th day of March, 1922.

WILLIAM ERASTUS WILLIAMS.
